Specification for Design.

Patented Mar. 12, 1912.

Application filed September 28, 1911. Serial No. 651,869. Term of patent 14 years.

To all whom it may concern:

Be it known that I, THOMAS A. DE VILBISS, a citizen of the United States, residing at Toledo, in the county of Lucas and State of Ohio, have invented a new, original, and ornamental Design for a Frame for Air-Brushes, of which the following is a specification, reference being had to the accompanying drawings, forming part thereof.

In the drawings, Figure 1 is a side eleva-

tion of a frame for air-brushes showing my new design, and Fig. 2 is a top plan view thereof.

I claim:

The ornamental design for a frame for air-brushes, as shown.

THOMAS A. DE VILBISS.
